UNITED STATES PATENT OFFICE.

CORA THEKLA ZALEWSKI, OF WATERLOO, ONTARIO, CANADA, ASSIGNOR TO THE WILLIAMS, GREENE & ROME COMPANY, LIMITED, OF KITCHENER, CANADA.

REVERSIBLE CUFF.

1,288,367.

Specification of Letters Patent. Patented Dec. 17, 1918.

Application filed April 8, 1918. Serial No. 227,341.

To all whom it may concern:

Be it known that I, CORA THEKLA ZALEWSKI, of the town of Waterloo, in the county of Waterloo, Province of Ontario, Dominion 5 of Canada, have invented certain new and useful Improvements in Reversible Cuffs, of which the following is a specification.

This invention relates particularly to soft double or French cuffs, and my object is to 10 devise a cuff of this type which will fold readily either way on its center, thus enabling the wearer to use it with either side out.

I attain my object by so cutting and 15 curing the interlining in place in the cuff that a line weakness is formed in the cuff at the middle, thus permitting the cuff to be folded with equal ease in either direction and with equal neatness in the fold.

20 The cuff is constructed in detail substantially as hereinafter described and illustrated in the accompanying drawings in which—

Figure 1 is a perspective view of a cuff 25 broken away to disclose the construction;

Fig. 2 a section, somewhat exaggerated, showing the cuff folded in one direction; and

Fig. 3 a similar view showing the cuff 30 folded in the other direction.

In the drawings like numerals of reference indicate corresponding parts in the different figures.

1 are two pieces of fabric forming the 35 facing of the cuff, each piece being turned right side out so that the pattern, if any, is displayed both inside and outside of the cuff. To the facing material is secured the interlining 2. This interlining is divided

40 on a line intermediate the top and bottom of the cuff and sewn to the facing material. The division between the interlining preferably extends entirely across the interlining, though it is not essential that it should ex-

45 tend through the margins which are contained within the hemmed edges of the cuff.

The division is preferably such that the two 50 pieces of interlining are separated by a narrow space, approximately one-eighth inch in width.

The interlining at each side of the division is sewn to the facing material of the cuff. The preferable arrangement is as shown in Figs. 1, 2 and 3, in which one piece of interlining is sewn to one of the pieces 55 of facing material and the other part of the interlining to the other piece of facing material. With this arrangement, whichever way the cuff is folded, no line of stitching is disclosed at the outside of the cuff, which 60 is of much importance, particularly with certain materials or patterns.

With this construction it will be found that the cuff will fold easily and perfectly either way, so that it may be worn with 65 either side out. Two important advantages are attained by this construction. In the first place the shirt may be used longer without being laundered, as it is usually the cuffs that become dirty long before the rest of 70 the shirt is soiled. With this cuff it is merely necessary to fold back the cuff in the opposite direction after one side has been soiled and replace the cuff links. In the second place, the life of the shirt is materially increased as the cuffs usually fray out first along the line of the fold, and with this present arrangement the wear is divided between two separate pieces of fabric. 75

What I claim as my invention is:— 80

A cuff formed of two separate pieces of facing material and a separate interlining, the latter being divided on a line intermediate the top and bottom of the cuff and sewn to the facing pieces at each side of the 85 division, whereby a line of weakness is formed along the middle of the cuff enabling the outer part of the cuff to be turned back in either direction, one part of the interlining being sewn to one facing piece only 90 and the other to the other facing piece only.

Signed at Kitchener, Ontario, this 22nd day of March, 1918.

CORA THEKLA ZALEWSKI.
